[57] CLAIM

The ornamental design for a bathtub, as shown and described.

DESCRIPTION

FIG. 1 is a top plan view of a bathtub showing my new design;

FIG. 2 is an elevational view taken from one side thereof, the opposite side being a mirror image of the side shown;

FIG. 3 is a right end elevational view thereof;

FIG. 4 is a cross sectional view taken on line 4—4 of FIG. 2; and

FIG. 5 is a cross sectional view taken on line 5—5 of FIG. 1.

*Fig. 1.**Fig. 2.**Fig. 3.**Fig. 4.**Fig. 5.*
